UNITED STATES PATENT OFFICE.

GEORGE E. SHIPWAY, OF NOROTON, CONNECTICUT, ASSIGNOR TO THE SALT'S TEXTILE MANUFACTURING CO., OF BRIDGEPORT, CONNECTICUT, A CORPORATION OF CONNECTICUT.

MANUFACTURE OF COLORED PILE FABRICS.

Application filed December 24, 1925. Serial No. 77,656.

This invention relates to the manufacture of colored pile-fabrics, particularly velvets.

A principal object of the invention is to provide a method of manufacturing pile-fabrics such as velvets in a practically unlimited range of colors, shades and tints from yarns dyed to standard shades in a relatively few selected colors.

Another object of the invention is to provide a method of producing colored velvets in a multiplicity of colors, shades and tints without requiring that the component yarns of the fabric be critically matched to the same shade in the dyeing.

Another object of the invention is to provide a method and process of manufacture whereby fabrics of many different colors and shades may be produced without changing the color of warp already in the loom, so that goods of the required color or shade may be more promptly supplied without waits or delays incident to the necessity for dyeing the warp yarns to match, winding and warping the same and drawing the new warp into the loom.

Another object of the invention is to provide for greater economy in the cost of manufacture of the goods by minimizing the number of colors and shades in which the yarns must be dyed and carried in stock; by eliminating the critical matching of a large number of shades in the dyeing; by saving time and labor required for changing warps in the loom; by the elimination of waste ends of warp yarns or wastage in yarn dyed to a shade which is supplanted or becomes obsolete; and through other economies as hereinafter set forth.

The improved method of manufacture and the resultant effects in the goods produced thereby are fully explained in the following specification which describes a type of fabric as illustrated in the accompanying drawings by way of example only. In the drawings:

Fig. 1 is a cross-sectional or profile view showing the structure of the weave for a usual type of velvet as woven double in the loom;

Fig. 2 is a diagrammatic view of the weave in perspective, showing the fabric with the yarns widely separated in an open mesh to more clearly illustrate their disposition;

Fig. 3 is an enlarged cross-sectional view illustrating the fabric in its final state; and

Fig. 4 is a chart or diagram illustrating the method of combining certain colors and shades in the component yarns of the fabric.

Velvets and other pile-fabrics are composed of three elements, the warp yarns, weft or filling yarns, and pile yarns. The warp and weft yarns constitute the ground or body of the cloth, and the pile threads are interwoven therewith with their floats standing more or less perpendicular to the ground or body and cut and frayed to form the pile tufts which constitute the soft, lustrous surface of the goods. All three of the yarn components show to the eye on the face of the cloth and the color and shade of the goods is dependent on the colors and shades to which the several different yarns are dyed.

In accordance with the usual practice of weaving velvets the yarn for the warp, weft and pile is all dyed to the same color and shade, and very careful and accurate dyeing is required to match a certain shade from sample, or to reproduce the same shade in a large number of pieces. Moreover if a large number of different shades are required in separate pieces the warp must be changed for each change from one shade to another, and the yarn for warp, weft and pile for the full requirements must be dyed in advance of manufacture and kept in stock. Obviously, therefore, when a large number of colors and a wide variety of shades in the colors are required, a very considerable investment in yarn in the many colors and shades is entailed, and often there is a heavy loss from waste in yarn of certain colors or shades whose popularity wanes, due to changes in the style or mode. Then again, where a certain color or shade attains exceptional popularity and the trade reorders in quantity, it usually requires weeks to dye a new supply of yarn to match the original and to prepare it for weaving by the several processes of winding, warping and twisting the warp into the loom. By the time the goods are completed the demand may have ceased and therefore a considerable loss may result to the manufacturer. Furthermore, where the popularity shifts from one color or shade to another without possibility of anticipating the demand, frequent changes

of the warp in the loom must be made and this entails much extra time and labor.

To obviate these unsatisfactory conditions common to the manufacture of pile fabrics

5 in large quantities in many colors and shades I have devised a new method of producing a multiplicity of colors with a practically unlimited range of shades in goods woven from component yarns dyed to a relatively few 10 shades in the primary colors. I have discovered that by employing two shades each of only three primary colors, with the addition of white and black, and effecting all the combinations of these eight colors and shades 15 by using any one for the warp, weft or pile while varying the colors or shades of the other elements, I can obtain a total of five hundred and twelve combinations, giving a like number of shades, no two of which make 20 the same impression on the eye, and many of which are novel effects of great distinction and beauty never before produced.

The details of my improved method of manufacture will now be more explicitly ex-

25 plained as an exemplification of the manner of carrying out the invention. Referring to Fig. 1 of the drawings, it is the preferred practice to weave pile fabrics double, that is with one fabric superimposed above the 30 other and the pile threads floating therebetween to be cut to separate the two pieces. In Fig. 1, H designates the loom harnesses through which the ground warp yarns *g*, *g* and pile warp yarns *p*, *p* are drawn to be 35 manipulated to open the shed for the passage of the shuttles carrying the weft or filling yarn. The shuttles *S* are carried on the oscillating lay *L* which also carries the reed *R* for beating the weft into the fell of the 40 cloth. The two strips of fabric *A* and *B* are woven by the interlacing of the weft yarns *w* with the ground warp ends *g*, and the pile warp threads *p* are also interlaced over and under the weft and floated between the two 45 ground fabrics in any suitable order, for instance with the usual weave for velvets as herein illustrated. The pile floats *f* are cut by a knife *K* and the separate fabrics feed over rollers *P* at the front of the loom to 50 be taken up by suitable wind-up rolls not herein illustrated.

Fig. 2 illustrates the arrangement of the 55 yarns in the fabric, the ground warp *g* being interlaced over and under the weft picks *w* in pairs, in alternate order across the width of the cloth, and the pile threads *p* looped under the weft picks in alternate order between the ground warp yarns *g*. In Fig. 60 2 the yarns are shown as widely separated, for the sake of clearness in the illustration, but actually the threads are disposed in close relation, see Fig. 3, so that the pile threads are held tightly bound into the ground of the fabric with their ends standing substantially 65 erect or in perpendicular relation thereto.

In the finishing of the goods the pile ends are frayed or burst to intermingle their fibers in a dense pile projecting from the face of the cloth.

While the pile in velvets may vary somewhat in density in accordance with the quality of the goods, even with a thick pile the color of the warp and weft yarns of the fabric have an appreciable effect upon the color or shade of the pile. That is to say, 70 all three component yarns show on the face of the goods and it has been found that each element of the combination has a stronger or weaker influence on the resultant shade of the fabric depending on the actual color 75 used. As a general rule, the pile has the greatest color value, the weft next, and the warp the least; although this ratio may be altered by a change in the character of the 80 weave or by other conditions. For example, 85 in the lighter shades, and especially with a white pile, the weft has the strongest color influence, the warp next and the pile the least.

After considerable experimenting I have 90 found that practically all colors may be produced in a maximum range of shades by using yarns dyed to two shades in the primary colors red, yellow and blue, while adding white and black in some of the combinations. For example, the two shades of red used in different order in the warp, weft and pile will give eight combinations, resulting in eight different shades of red in the 95 fabrics produced therefrom. This is shown 100 graphically by the chart or diagram of Fig. 4, in which the component yarn elements are designated as follows: *g* for ground warp, *w* for weft, and *p* for pile; with the two shades of red numbered 1 and 2. To 105 extend the range, the white and black yarns may be introduced in varying order in the combinations, the result being a multiplicity of shades of the one color element too numerous to here catalog.

Now by introducing another primary color into the combinations still different hues of varying shades are arrived at. For example, with red and yellow yarns combined in different order practically all shades of orange 115 may be obtained in the goods, and many other tints or tones may be produced with the introduction of the white and black 120 yarns.

Again, with combinations of the primary colors yellow and blue a full range of green shades may be produced and these further toned with white or black. Likewise, combinations of red and blue in the yarn components will produce the color of violet in 125 the fabric, and this may be toned to heliotrope, purple and other shades through the use of white and black.

Where two different standard primary colors are combined in different shades the 130

resultant colors and shades will conform to a certain standard, although in combinations employing white for the pile the effect is quite unique and very beautiful as giving a silvery or frosted cast to the color. When a third primary color is introduced into the combinations the unique effect is still further enhanced, many apparently new and surprising hues being attained, in all too numerous to mention and so beautiful as to defy description.

It will be understood, of course, that velvets are usually woven from silk yarn, at least for the pile, and on account of their gloss the threads have certain reflective powers or characteristics which cause two or more colors or shades in the component yarns to merge or blend to give a different shade to the whole piece. For instance, with a red pile and blue ground, the red pile threads will reflect the blue color of the ground, and the blue yarns in the ground will reflect the red of the pile, so that the effect produced on the eye is as the combination of these two primaries, giving violet, purple, and other shades as the case may be. As the observer looks across the face of the goods at different angles the shade appears to change somewhat as the ground colors lose part of their influence on the standing pile threads, yet still the ground will always tone the pile to some extent, and when the goods are draped in folds the shading of the colors gives extraordinarily beautiful iridescent effects.

I am aware that heretofore in the manufacture of the cheaper grades of velvet it has sometimes been the practice to use warp and weft of a darker shade from that of the pile to avoid the necessity of matching the yarns of the ground or body of the cloth to the exact shade of the pile. This can only be done with the darker shades, however, being no more than a makeshift and never employed for the finest and most expensive fabrics. In the cheaper grades of blue velvets, for instance, a black weft is sometimes used to obtain a darker shade with a warp and pile of standard shade, thus avoiding changing the warp in the loom, but this practice obviously has limitations and has never comprehended the combination of complementary colors in the manner as herein explained.

In some examples of upholstery goods the pile has a different color from the ground, but such combinations are for contrast, being usually employed in cut pile fabrics where the pile is removed to form a raised or embossed pattern with the contrasting background showing between the figures of the design.

In the so-called changeable silks of plain weave two or more colors are introduced to obtain harmonious color contrasts shading from one to another, but here the direction

of the light gives the changing effects and the colors cannot be combined to give a distinct complementary hue in all lights, because there is no pile standing on the face of the goods to reflect the color of the ground with a complete blending therebetween.

As before stated, an important and far-reaching advantage of the present improved method of manufacture results from the fact that I am able to produce goods in a practically unlimited number of colors, and with a maximum range of shades, from yarns dyed in only a few primary colors. As before explained, the three primary colors above noted used in two shades each, with white and black added, will give five hundred and twelve distinctive shades, not only meeting the usual requirements as regards the standard range of colors and shades, but also providing many unique hues and original effects. This results in great economies in cost of manufacture, elimination of waste, reduction of stock and finished materials to be carried, and a saving in time required to produce or reproduce goods to given requirements.

Instead of the usual stock of several hundred colors of yarn the manufacturer can with only eight colors produce any one or more of the five hundred and twelve shades for prompt delivery, and by following certain formulæ can reproduce these many shades as required for reorder, without delays for dyeing and matching, and preparing and drawing in new warps; it being understood that a single color of warp may serve for many combinations. Ordinarily, it has been the practice to carry a stock of yarn prepared for warp, weft and pile for all standard colors and shades, and when a slight variation from standard is specified the grey yarn must be sent to the dyehouse, a small sample dyed and returned to check for matching, then the whole lot dyed and shipped in, after which it is wound and warped and then twisted into the loom. This entails a delay of several weeks and there is usually a certain amount of the yarn of the particular color left over which must be disposed of as waste. With a small number of colors a relatively large stock of yarn may be carried in each without an excessive stock in the aggregate. The yarns of the several colors are all prepared in the form of warp, weft and pile, thus saving much time and practically eliminating waste, while requiring a much smaller investment with practically no dead stock.

It is to be understood that while white, technically, is not a color but a combination of the primary colors and black the absence of color, the term color as herein employed in the specification and claims is to be construed broadly as including black and white.

While I have herein explained a preferred manner of carrying out the improved method of manufacture as adapted to usual requirements, it is obvious that the details thereof may be varied considerably without departing from the spirit or scope of the invention, I believe I am the first to devise a method for producing pile fabrics in a plurality of colors with a wide range of shades from combinations of yarns dyed in a relatively small number of primary colors and I desire to claim this method and the result broadly.

I claim:

15 1. As a new article of manufacture, a velvet fabric woven from warp, weft and pile yarns dyed respectively to different colors and combined in the weave to blend the several colors to give the pile a different color as the face of the fabric is viewed from various angles.

25 2. As a new article of manufacture, a colored velvet fabric woven from warp, weft and pile yarns dyed respectively to different shades and combined in the weave to blend the several shades to modify the color of the pile on the whole piece of goods as its face is viewed from various angles.

30 3. As a new article of manufacture, a velvet fabric woven from warp, weft and pile threads dyed in the yarn to two or more primary colors and combined in the weave to blend to produce a different color of the pile on the whole piece of goods as its face is viewed from various angles.

35 4. An improved method of manufacturing velvet fabrics consisting in selecting yarns dyed to different colors for the warp, weft and pile components of the cloth and

combining the colors in the weave to blend them to produce a different color or shade of the pile on the whole piece of goods as the fabric is viewed on its face from various angles.

45 5. An improved method of manufacturing colored velvets consisting in dyeing yarns to several colors for the warp, weft and pile components of the cloth and weaving separate lengths of fabric from different combinations thereof whereby the several colors in each piece are blended to produce a wide variety of hues and shades of the pile on the different pieces as the fabric is viewed on its face from various angles.

50 6. An improved method of manufacturing velvet fabrics in a full range of colors, shades and tints consisting in dyeing yarns to a relatively small number of primary colors in different shades and weaving the fabrics from different combinations thereof in the warp, weft and pile whereby the colors are blended to produce a wide variety of colors, shades and tints in the pile on different pieces of the goods as the face of the fabric is viewed from various angles.

60 7. An improved method of manufacturing velvet fabrics consisting in dyeing yarns to different colors and shades, for example in two shades of each of three primary colors with the addition of white and black and weaving lengths of fabric with various combinations of the original colors and shades in the warp, weft and pile which are blended to produce a variety of colors and shades in the pile on the several pieces of the goods when the face of the fabric is viewed from various angles.

In testimony whereof I affix my signature.

GEORGE E. SHIPWAY.
